UNITED STATES PATENT OFFICE.

CHARLES E. GODLEY, OF DETROIT, MICHIGAN, ASSIGNOR TO EDMUNDS AND JONES MANUFACTURING COMPANY, OF DETROIT, MICHIGAN, A CORPORATION OF MICHIGAN.

LAMP.

1,074,312.

Specification of Letters Patent.

Patented Oct. 7, 1913.

Application filed May 12, 1913. Serial No. 767,111.

To all whom it may concern:

Be it known that I, CHARLES E. GODLEY, a citizen of the United States, and a resident of Detroit, in the county of Wayne and State of Michigan, have invented a new and Improved Lamp, of which the following is a specification.

This invention relates to lamps especially adapted for automobiles and other vehicles, and its object is to provide a construction which, when mounted on a vehicle, will not rattle; will be strong; will be attractive; and can be readily opened for cleaning.

This invention consists in a lamp comprising a body, a reflector and a ring supporting the lens, together with springs mounted between the body and the reflector in such a manner that the reflector will be pressed against the lens to prevent both from rattling, and to prevent the entrance of air and moisture.

It further consists in the use of bayonet-joints in connection with both the reflector and the cap to unite them with the body.

In the accompanying drawings Figure 1 is a side elevation and Fig. 2 a vertical longitudinal section of this improved lamp. Fig. 3 is a front elevation of the lamp, a portion of the lens-supporting ring being broken away. Fig. 4 is a side elevation of the front portion of the lamp with parts of the lens-supporting ring broken away in order to show the interior arrangement. Fig. 5 is a section on the line 5—5 of Fig. 1. Fig. 6 is a front elevation of the lamp with the lens-supporting ring removed. Fig. 7 is a side elevation of a small portion of the lamp. Fig. 8 is an elevation of the front end of the body. Fig. 9 is a side elevation of a small portion of the body showing one of the springs. Fig. 10 is a rear elevation of a modified form of lamp. Figs. 11, 12 and 13 are sections on the lines 11—11, 12—12 and 13—13 of Fig. 10 respectively.

Similar reference characters refer to like parts throughout the several views.

The body 1 of this lamp is substantially parabolic and has a reinforcing device 2 fitted to it and secured in place by means of rivets 3. See Fig. 2. An insulating member 4 within this reinforcing member supports the rods 5 by which this lamp may connect to a current source and to which are connected the wires 6 that lead to the base 7 of the lamp 8. This lamp may be revo-

lably and frictionally mounted in substantially the focus of the parabolic reflector 9. The parts thus far described form no part of this invention.

Referring to Figs. 5, 8 and 9, the body 1 is shown formed with a cylindrical portion 10 and an inwardly turned flange 11, which carries the headed posts 14 and the springs 12, held in position by the bolts 13. In the flange 11 are three holes 15 for the stop pin 16, three holes being drilled and tapped so that the pin can be inserted, no matter how the reflector is inserted.

The body of the reflector is parabolic, and at its edge it is provided with a grooved rim 17 to receive the cord or cushion 18 which is pressed against the lens, and therefore, transmits pressure to the supporting ring and prevents rattling. Just outside of the grooved rim is a backwardly extending cylindrical portion 19 and at the rear edge of this cylinder is a radial flange 20 having slots 22 to permit the relative circular movement of the posts 14, the key-hole slots 23 to receive the bolts 13, and a hole to permit the entrance of the stop-pin 16.

When it is desired to mount the reflector on the body, the lamp base 7 is inserted in the opening in the rear end of the reflector and the reflector is inserted in the body to about the position shown in Fig. 2 with the bolts 13 passing through the enlarged ends of the slots 23, and the posts 14 through the slots 22, the reflector resting against the springs 12. The reflector is then pressed back into the body, compressing the springs 12 so that the heads of the bolts 13 will extend beyond the face of the flange 20, as shown in Fig. 7, sufficiently to permit the reflector to be turned and thus relatively carry the bolts 13 to the opposite ends of the slots 23, as shown in Fig. 6. The locking pin 16 is then passed through a hole in the flange 20 and screwed into one of the holes 15 in the flange 11 of the body, thus holding the reflector from turning in the body. The bolts 13, posts 14 and holes 15 are evenly and exactly spaced so that there is no difficulty in positioning the reflector.

The lens 25 is of any desired curvature, and is mounted in a hollow supporting ring formed of two thicknesses, as shown in Fig. 5. The outer thickness 26 is substantially semi-circular in cross-section while the inner thickness is formed of three cylinders 27, 110

28 and 29, joined by radial flanges 30 and 31. In Fig. 3, the front portion of the part 26 is broken away to show the flange 31 which is provided with key-hole slots 32 to receive the heads of the posts 14, and slots 33 to receive the locking pin 16, just described. This pin is made of such length in order that it can be easily placed and removed, but if desired, it can be made somewhat shorter and the slots 33 omitted. This lens 25 is held in position by small plates 35 on the rear side of the flange 31, the bolts 36 and nuts 37. The plates 35 are so thin that they may be pressed into the cushion 18.

15 When the lens and its supporting ring are to be attached to the body, the ring is positioned so that the cylindrical portion 27 will fit around the ring 10 of the body; the posts 14 enter the slots 32; and the screw 16 enters one of the slots 33. The ring is then pressed against the rim 17 of the reflector, against the tension of the springs 12, until the heads of the posts 14 extend beyond the flange 31. The ring and lens are then turned (to the right in Fig. 3) until the posts 14 are in the smaller ends of the key-hole slots 32. A screw 40, mounted in a sleeve 41 between the parts 26 and 30 of the lens-supporting ring, can then be turned in until its inner end extends inwardly to the right of and beyond the adjacent post 14, as shown in Figs. 2, 3 and 5. This will prevent the ring and lens from being turned to the left. When the lens-supporting ring is thus positioned, it 35 will press against the cushion 18 sufficiently to compress the springs 12, as shown in Fig. 4. As a result, all rattling is obviated, and entrance of air and moisture prevented.

Instead of mounting the lens-supporting 40 ring on the posts 14, it may be provided with lugs 45 which fit between the ears 46 on the body 47, as shown in Figs. 10 and 11. The parts 48 and 49 of the body 1 and lens-carrying ring near the line of the parts 46 and 47 may be at a slightly different angle than the parts 10 and 27 in the other form, or the same parts on the line 12—12 of Fig. 10, and the posts 14 will be entirely omitted. The screws 13 position the springs 12 which hold 45 out the reflector, which is connected to the body in the manner previously described. The rim may be pivoted permanently on one of the pins 50 or both of the pins can be removed each time the lamp is to be opened. 50 When the ring is held in position by both pins, the reflector flange 20 will compress the springs 12, as shown in Fig. 13, tensioning them so that the cushion 18 will be so firmly pressed out against the flange 31 and 55 the lens 25 that rattling of the parts becomes impossible, and entrance of air and moisture is prevented.

I claim.

1. In a lamp, the combination of a cup-shaped body having a radial inwardly

turned flange at its edge, headed bolts mounted on the flange, arched springs mounted between the heads of the bolts and the flange, a parabolic reflector having a grooved rim and a circumferential flange provided with key-hole slots to receive the bolts projecting from the body, a cushion in the groove of the rim of the reflector, a ring and a lens carried thereby, and means to removably secure the ring to the body and hold it against the rim of the reflector in such a manner as to compress said springs. 70

2. In a lamp, the combination of a body having a circular edge, headed bolts extending at right angles to said edge, springs mounted on the bolts, a reflector having a grooved circular rim and a circumferential flange provided with key-hole slots to receive the headed bolts on the body, a circular cushion mounted on the grooved rim, a ring 80 and a lens carried thereby, and means to connect the ring to the body in engagement with the reflector in such a manner as to compress said springs. 85

3. In a lamp, the combination of a body 90 having a circular edge, bolts carried thereby, springs on the bolts, a reflector extending into said body and having a circular flange formed with holes through which the bolts extend, a lens-supporting ring in engagement with the reflector, and means to secure the ring to the body and in contact with the reflector so as to compress said springs. 95

4. In a lamp, the combination of a body having an opening, a ring and a lens secured over the opening, a reflector slidably mounted within the body, guides for said reflector mounted on the body and resilient means to press the reflector against said ring. 100

5. In a lamp, the combination of a body 105 having an opening, bolts mounted thereon around the opening, a ring and a lens mounted on the bolts over the opening, a reflector slidably mounted in the body on said bolts, and springs mounted between the body and the reflector to hold the latter against the ring. 110

6. In a lamp, the combination of a body having a circular opening and an inwardly turned flange at the edge of the opening, a 115 series of bolts and headed posts mounted on the flange, a ring having key-hole slots into which said headed posts extend by means of which the ring is secured to the body, a lens carried by the ring, a parabolic reflector having a grooved rim and a flange having holes through which said bolts extend, springs on the bolts between the flanges on the body and the reflector to hold the reflector outward against the lens, and an annular 120 cushion in the grooved rim of the reflector in contact with the lens. 125

7. In a lamp, the combination of a body having a circular edge, longer and shorter headed bolts extending at right angles to 130

- said edge, springs mounted on the shorter bolts, a reflector having a circumferential flange provided with slots to receive said bolts, a ring and a lens carried thereby, said 5 ring having key-hole slots to receive the longer headed bolts when pressed against said reflector sufficiently to cause the compression of said springs, and means to prevent the lens from turning.
- 10 8. In a lamp, the combination of a body having an opening, headed bolts mounted on the body around the opening, a ring and a lens mounted on the bolts over the opening and held in position by said bolts, a reflector 15 slidably mounted on said bolts in said opening, and springs between the body and the reflector to hold the reflector against the ring and the ring against the heads of said bolts.
- In testimony whereof I have signed this 20 specification in the presence of two subscribing witnesses.
